(51) LOC (8) Cl. **26-03**

(57) **CLAIM**

(52) U.S. Cl. **D26/80; D26/138; D26/2**

We claim the ornamental design for a light emitting diode lamp unit, as shown and described.

(58) **Field of Classification Search** D26/2,
D26/80, 86, 138; D13/180, 182; 313/512;
362/555, 612, 800, 231, 235, 237, 240, 241,

FIG. 1 is a top perspective view of first embodiment of a light emitting diode lamp unit of the present invention;
FIG. 2 is a top view thereof;
FIG. 3 is a bottom view thereof;
FIG. 4 is a first side view thereof, wherein the second side view is a mirror image thereof;
FIG. 5 is a third side view thereof, wherein the fourth side view is a mirror image thereof;
FIG. 6 is a top perspective view of second embodiment of a light emitting diode lamp unit of the present invention;
FIG. 7 is a top view thereof;
FIG. 8 is a bottom view thereof;
FIG. 9 is a first side view thereof, wherein the second side view is a mirror image thereof; and,
FIG. 10 is a third side view thereof, wherein the fourth side view is a mirror image thereof.
